UNITED STATES PATENT OFFICE.

GEORGE COSTOLO, MARY JANE COSTOLO, AND ALFRED JOHNSON, OF UNION-TOWN, PA.; SAID JOHNSON ASSIGNOR TO SAID GEORGE COSTOLO.

CAR-COUPING.

SPECIFICATION forming part of Letters Patent No. 288,925, dated November 20, 1883.

Application filed September 19, 1883. (No model.)

To all whom it may concern:

Be it known that we, GEORGE COSTOLO, MARY J. COSTOLO, and ALFRED JOHNSON, citizens of the United States, residing at Uniontown, in the county of Fayette and State of Pennsylvania, have invented a new and useful Car-Coupling, of which the following is a specification, reference being had to the accompanying drawings.

10 This invention relates to car-couplings; and it has for its object to provide an improved device which shall possess superior advantages in point of simplicity, durability, and general efficiency, as will be hereinafter fully 15 described, and particularly pointed out in the claims.

In the drawings hereto annexed, Figure 1 is a top view of our improved car-coupling. Fig. 2 is a bottom view of the same. Fig. 3 is 20 a longitudinal vertical sectional view. Fig. 4 is a transverse vertical sectional view, and Fig. 5 is a detail view.

The same letters refer to the same parts in all the figures.

25 A in the drawings designates the draw-head, which is provided with a longitudinal slot, B, having flanges C upon its inner sides, and provided at its front end with a mouth, D. Fitted upon the upper side of the flanges C is a slide, E, the front end of which has a forked recess, F. Upon the under side of the flanges C moves a slide, G, which is connected with the slide E by a bolt, H, working in the slot B. The slide G has a rearwardly-projecting arm, 30 I, between which and the rear end of the draw-head is coiled a spring, J, serving to force the said slide, and with it the slide E, in a forward direction. The draw-head A is provided with laterally-projecting arms K K, upon which are 35 pivoted levers L L, the inner ends of which bear against studs M M, projecting downwardly from the front end of the plate or slide G, which may, by the action of the said levers, be forced in a rearward direction. The upper 40 side of the mouth D of the draw-head is provided with a rearwardly-extending slot, N, in which is pivoted an arm or lever, O, having at its rear end an eye or opening, P, to receive a coupling-pin, Q. When the latter is in position, it may, by the action of the incoming

link, be thrown in an upward and rearward direction, thus permitting the link to enter the draw-head and complete the coupling automatically. To the sides of the draw-head are pivoted the ends of a bail, R, which extends 55 under the draw-head, and is provided with forwardly-extending arms S S, the forward ends of which have pins T T extending upwardly through openings U U in the under side of the draw-head, so as to be capable of 60 forcing the front end of the link in an upward direction when the under side of the said bail is forced forwardly by the action against it of either of the levers L. The front end of the slide E has a recess, V, in its under side, to 65 receive the rear end of the coupling-link and retain the latter in a level position.

The operation of this invention will be readily understood from the foregoing description, taken in connection with the drawings hereto 70 annexed. The front end of the link may be raised or lowered to any desired extent, thus causing it to enter the draw-head of the next car without fail. The construction of the device is simple, and it may be easily operated. 75

We claim as our invention and desire to secure by Letters Patent of the United States—

1. In a car-coupling, the combination of the draw-head having flanges upon its inner adjoining sides, the slides moving upon the upper and lower sides of said flanges, a bolt connecting the said slides, a pair of levers pivoted to brackets projecting laterally from the draw-head, and studs projecting downwardly from the lower slide and acting against said levers, 80 substantially as set forth.

2. In a car-coupling, the combination of the draw-head, constructed substantially as described, the slides E and G, a forked recess at the front end of the slide E, a lever pivoted in a 85 recess at the front end of the mouth of the said draw-head, and a coupling-pin arranged in an opening at the rear end of the said lever, and a pair of levers arranged so as to be capable of moving the slides E and G in a rearward direction, substantially as set forth.

3. The combination of the draw-head, constructed substantially as described, and having the slide E, provided with a forked recess at its front end, the coupling-link adapted to 95 100

be retained under the front end of the said slide, a bail pivoted to the sides of the draw-head and extending under the same, and having forwardly-projecting arms provided with 5 studs that extend upwardly through openings in the under side of the draw-head, and the levers pivoted to brackets extending laterally from the sides of the draw-head, and adapted to force the bail aforesaid in a forward direction, substantially as set forth.

In testimony that we claim the foregoing as our own we have hereto affixed our signatures in presence of two witnesses.

GEORGE COSTOLO.
MARY JANE COSTOLO.
ALFRED JOHNSON.
